UNITED STATES PATENT OFFICE.

GEORGES A. BROUILLET, OF BROOKLINE, MASSACHUSETTS.

PROCESS OF FILLING TEETH.

1,126,949.

Specification of Letters Patent.

Patented Feb. 2, 1915.

Application filed November 10, 1914. Serial No. 871,384.

To all whom it may concern:

Be it known that I, GEORGES A. BROUILLET, a subject of the King of Great Britain, residing at Brookline, county of Norfolk, 5 State of Massachusetts, have invented an Improvement in Processes of Filling Teeth, of which the following description, in connection with the accompanying drawing, is a specification, like characters on the drawing representing like parts.

10 This invention has for its object to provide a novel process of filling teeth by which the operation of filling a cavity with any plastic filling can be greatly facilitated.

15 There has developed in the practice of dentistry a so-called porcelain filling which has many advantages when it is properly used. This type of filling material, however, is rather difficult to manipulate because 20 it sets very quickly and it cannot be molded or worked at all after it begins to set, and unless the dentist is very skilful and operates rapidly an imperfect filling is likely to result.

25 My invention provides a novel process by which the filling of a cavity, and especially a side cavity, with this porcelain filling can be greatly facilitated.

30 In order to give an understanding of the invention, I have illustrated in the drawings a selected embodiment thereof which will now be described, after which the novel features will be pointed out in the appended claims.

35 In the drawings, Figure 1 is a perspective view of a matrix which may be used in practicing; Figs. 2 and 3 are views showing the way in which the matrix is used and the way in which my improved method is carried out.

40 I have indicated three teeth at 1, 2 and 3, respectively, the tooth 2 being shown as having a side cavity 4 therein. In filling this cavity in accordance with my improved 45 method, I first provide a matrix 5 made of flexible material and of a size to fit closely about the defective tooth, and of a shape to present an extension 6 that projects beyond the grinding surface of the tooth when the 50 matrix is in position. In the practical manufacture of these matrices, I purpose to make each matrix with two projections 6 situated opposite each other, but one projection only is necessary for filling many cavities.

55 In carrying out my improved method the

cavity 4 is first cleaned, as usual, and then the matrix 5 is applied to the tooth in such a position that the extension 6 will be situated on the side of the tooth having the cavity therein which, as herein illustrated, is the side of the tooth adjacent the tooth 3. The matrix will be of such a size, as above pointed out, that when it is placed about the tooth the extension 6 will project beyond the 60 grinding surface of the tooth. After the matrix is properly placed about the tooth, a wedge member 7 will preferably be inserted between the matrix and the tooth 3 near the gum so as to hold the matrix close to the tooth 2 and separated from the tooth 3 at the gum. When the matrix is thus in position it forms the exterior wall of the cavity 4 which may then be filled with the porcelain cement 8. This porcelain cement is 70 mixed to make a plastic cementitious mass and when in this plastic state it is inserted into the cavity 4, the cavity being filled to the desired extent. This operation must be done comparatively quickly because this 75 porcelain cement begins to set rapidly and a good filling cannot be made if the cement is worked at all after it begins to set. When the cavity has been properly filled, then the extension 6 adjacent the cavity is folded 80 over on the top of the filling 8, as shown in Fig. 3, and this extension is held in its folded position either by the finger of the dentist, or by means of an instrument, such as shown in dotted lines at 9, for two or three 85 minutes, or until the porcelain filling has set sufficiently so that it will not adhere to the matrix. In thus folding the extension 6 over the exposed surface of the filling and holding it there, a slight pressure will be 90 applied sufficient to cause the matrix to 95 bulge outwardly slightly, as at 10, until it contacts with the tooth 3, thus giving the filling 8 the proper shape at the approximal part to restore the desired natural contact 100 between the teeth 2 and 3. When the filling is properly set, the matrix is removed and a filling 8 of the proper shape is thus produced.

105 The matrix 5 is of flexible material which will readily adapt itself to the desired shape of the filled tooth and which will permit the extension to be folded over, as shown, and will also preferably have a smooth interior surface so that when it is folded over 110 against the filling it will give the exposed face of the latter a smooth surface, thus

2
obviating the necessity of filing or scraping the surface of the filling to smooth the latter.

I find that celluloid makes a good material of which to make these matrices.

5 The matrix shown in Fig. 1 is also provided with extensions 11 at the sides so that if the cavity is one that extends below the gum and the matrix is applied to the tooth, the extension 11 will project down far 10 enough to form a side wall for the cavity throughout its entire extent without necessitating the crowding of the matrix upon the tooth to such an extent as to injure the gums. These extensions 11 will be trimmed off more 15 or less by the dentist to fit the particular tooth to which the matrix is to be applied.

I claim:

1. The process of filling a compound cavity of a tooth which consists in placing about 20 the tooth to be filled an annular matrix of flexible material having an extension on the cavity side of the tooth, which extension projects beyond the tooth, filling said cavity as bounded by the matrix with a cementitious filling, folding the extension of the 25

matrix over the end of the tooth and into contact with the exposed portion of the filling, and holding said extension in this position until the filling sets.

2. The process of filling a compound cavity of a tooth which consists in placing about 30 the tooth to be filled an annular matrix of flexible material having an extension on the cavity side of the tooth, which extension projects beyond the tooth, filling said cavity 35 as bounded by the matrix with a cementitious filling, folding the extension of the matrix over the end of the tooth and into contact with the exposed portion of the filling, forcing the matrix at the fold thereof 40 outwardly against the adjacent tooth, and holding said extension in this position until the filling sets.

In testimony whereof, I have signed my name to this specification, in the presence of 45 two subscribing witnesses.

GEORGES A. BROUILLET.
